UNITED STATES PATENT OFFICE

CHARLES K. DUNLAP, OF HARTSVILLE, SOUTH CAROLINA, ASSIGNOR TO SONOCO PRODUCTS COMPANY, OF HARTSVILLE, SOUTH CAROLINA, A CORPORATION OF SOUTH CAROLINA

METHOD OF MAKING BOBBINS

Application filed November 25, 1927, Serial No. 235,691. Renewed August 22, 1929.

The present invention relates to bobbins for use in the textile industry as cores or supports for thread windings.

The object of the invention is, stated generally, to provide a bobbin that can be produced at a small cost and which is not only suitable for use as a shipping carrier of fine or fragile threads, such as "rayon", but which can also be used without difficulty in a machine for manufacturing the thread into a fabric.

Heretofore it has been the custom of manufacturers of "rayon" and other fragile thread to wind the thread upon a relatively large core, usually of paper, for shipment to the place of consumption, where it was necessary to rewind the thread on a suitable bottle bobbin or cone before it could be used in the knitting or other fabric forming machine.

Some manufacturers have shipped their thread in skeins, and in these cases it was also necessary of course to wind the thread on a suitable bobbin before it could be fed into a machine. This rewinding is very undesirable, particularly in the case of rayon and other fragile threads, since it stretches the thread, thereby lowering its physical qualities and shortening its life. Three rewinds, for instance will practically destroy rayon.

The rewinding step heretofore found expedient can be eliminated if there can be produced economically a bobbin that is suitable both as a charging and transporting core for the thread and as a support for the thread in a fabric forming machine. A bottle bobbin is a suitable instrument for this purpose, but heretofore the only satisfactory bobbins of this type have been made of wood, and due to their weight and very considerable cost, it has been impractical for manufacturers of thread to buy and use the many thousands of such bobbins necessary to take care of their output. A suitable paper bobbin of this type would solve the difficulty, due to its lightness and comparatively small cost of production, but although some have been proposed and shown in prior patents, no satisfactory paper bobbin of the bottle type has heretofore been produced, so far as I am

aware. A bottle bobbin, in order to be capable of use in a knitting, or other fabric forming machine particularly those of the high speed type, must have its tubular and frustroconical surfaces exactly centered and co-axial and these surfaces must be truly cylindrical and conical respectively, since, due to the rapid rotation of the bobbins in use, any eccentricities of the surfaces cannot be tolerated. Another important requisite is that the joint between the conical and tubular parts be smooth, with no perceptible shoulder at the junction line. If a shoulder is left, the thread will pile up under it in winding, which of course results in unsatisfactory unwinding at this point.

As will be clear hereinafter, the present invention produces by means of a novel method of forming and assembling the tubular and conical members a paper bobbin which has its conical and cylindrical surfaces precisely centered and which has said surfaces smoothly merging without a perceptible shoulder at the junction line. The invention therefore provides a paper bottle bobbin which is entirely suitable as a support for a thread package in a knitting, or other, machine, and which, due to its lightness and small cost, is a practical charging and shipping core for the use of thread manufacturers.

Referring to the accompanying drawings:—

Fig. 1 is a side elevation of an apparatus suitable for reaming out the interior of the conical part of a bobbin;

Figs. 2 and 3 are sectional detail views on a larger scale, showing co-acting members of the apparatus in different positions;

Fig. 4 is a longitudinal sectional view through a cone which has been subjected to the operation of the apparatus shown in Figs. 1 to 3;

Fig. 5 is a side elevation (somewhat diagrammatic) of a machine for assembling the conical and tubular members forming a bobbin;

Figs. 6 and 7 show parts of the apparatus of Fig. 5 on a larger scale and in two different positions; and

Fig. 8 is a side elevation of a finished bobbin, partly broken away to show the joint between the two portions thereof.

Referring first to Figs. 1 to 3 for a description of the machine for preparing a paper cone for assembly with a paper tube to form a bottle paper bobbin in accordance with the present invention:—Fig. 1 shows somewhat diagrammatically a machine suitable for reaming out the lower ends of the cones to form therein cylindrical surfaces which are adapted to fit over and be secured upon one end of a paper tube or barrel. As shown, the operating parts of the machine are mounted on a frame or standard 10, said operating parts comprising a rotary cylindrical reamer 11 and a vertically reciprocable holder, or chuck, 12. The cutter 13 of the reamer is threaded on the lower end of a hollow cylinder, or pipe 14 and has a sharp serrated cutting edge, as indicated. The pipe 14 is rotatable in vertically spaced and aligned bearings 15 and 16 which are rigid with the upper portion of standard 10, and has fixed thereon between these bearings a pulley 17. Rotation is imparted to the cutter by a belt 18 which passes around pulley 17 and over an idle guide pulley 19 and around a drive pulley 20 which is driven by a suitable motor (not shown).

The chuck 12 is frustro-conical in form and may have its lower smaller end integral with a cylinder 21. Cylinder 21 is mounted for vertical reciprocation in a bearing 22 rigid with frame 10, and is formed with a collar 23 adapted to engage bearing 22 to limit the downward movement of the chuck. Bearing 22 is aligned with bearings 15 and 16, so that the axis of chuck 12 is maintained in exact coincidence with the axis of reamer 11. The chuck is adapted to be raised by a foot lever 24 which is fulcrumed at 25 on the base of upright 10. This lever is connected by a link 26 to one arm of a lever 27, the other arm of which is bifurcated and slotted to receive pins projecting laterally from the lower end of pipe 21. The chuck is biased to the lower position shown in Fig. 1 by gravity or by a suitable spring or by both.

A cone previously wound by known methods and preferably one which has had its exterior surface ground and finished in accordance with the method described in my Patent 1,634,492, is placed in chuck 12, as shown in Fig. 1. The interior conical surface of the chuck is of such dimensions that when the cone is seated therein the lower end of the cone will project very slightly within the pipe 21, as indicated in Fig. 2. With the cone thus positioned and the cutter 13 rapidly rotating, the operator depresses the foot lever 24 and thereby raises the chuck with the cone therein to the position shown in Fig. 3. In moving to this position the cutter reams out the lower end of the cone, form-

ing a true cylindrical surface in said lower end which is precisely co-axial with the axis of the exterior surface of the cone, and which meets the exterior conical surface at a very sharp angle, forming a feather edge, as indicated in Fig. 4. It is to be observed that the diameter of cutter 13 is substantially equal to the internal diameter of pipe 21, as indicated in Fig. 3, and therefore produces a very sharp feather edge at the small end of the cone. The nose or apex of the cone, severed by the reaming operation, may be blown out through the lower end of pipe 21 by an air blast delivered from a tube 30 which extends down through pipe 14 to a point adjacent the cutter, or may be removed by a suitable mechanical means. When the reaming operation is finished, the operator releases lever 24, which permits the chuck to drop away from the reamer so that the cone may be removed from the chuck and another inserted.

The cone prepared in accordance with the above method is adapted for assembly with the cylindrical part, or barrel, to form the finished bottle bobbin. It is important, and indeed essential, that the barrel be in precise co-axial position with respect to the cone in the finished bobbin, since in use the bobbins are rotated at a high rate and any eccentricity or angularity of the axes of these parts would render the bobbins useless. Figs. 5, 6 and 7 illustrate an apparatus which is adapted to assemble the parts of the bobbin in such a way as to insure an exact centering thereof. The operating parts of this apparatus are mounted on a frame F, and comprise a stationary arbor 31 and a reciprocable chuck 32. Arbor 31 may consist of a metal cylinder secured in vertical position on an offset part 33 of frame 30. The upper portion of this cylinder has a reduced diameter substantially equal to the interior diameter of the cylindrical portion, or barrel of the bobbin, an annular shoulder being formed at the junction of this upper portion with the lower portion of the cylinder, the width of the shoulder being equal to the thickness of the barrel, so that when a barrel is placed over the reduced upper portion of the arbor its lower edge will rest on said shoulder. The chuck 32 consists of a cylinder cored out to form an upper cylindrical part 34 and a lower frustro-conical part 35 adapted respectively to receive the cylindrical and frustro-conical portions of the bobbins. The chuck is cored out very accurately so that the cylindrical and conical portions thereof are exactly co-axial and are adapted to form a nice fit with the corresponding portions of the bobbins. Chuck 32 is attached to a stem 36 which is guided for reciprocation in vertically spaced and aligned bearings 37 formed on an offset portion of frame 30, the chuck being thus supported and maintained co-axial with arbor 31. The upper end of stem 36 is pivoted to the lower end 130

of a link 38, the upper end of which is pivotally connected to a pin 39 secured to a crank 40 on a shaft 41. Loose on shaft 41 is a gear 42 in mesh with a pinion 43 fixed on a shaft 44 which carries fast and loose pulleys 45 and 46 adapted to receive a driving belt (not shown). Gear 42 is adapted to be clutched to shaft 41 by means of a clutch 47 of any suitable form. This clutch is controlled by a foot lever 49 fulcrumed at 50 on the base of the frame and connected to the clutch by a rod 51.

The paper tube 52 constituting the barrel of the bobbin is formed in accordance with 5 any suitable method. It should have its exterior surface as nearly cylindrical as possible and of a diameter equal to the diameter of the cylindrical interior surface in the lower end of the cone to which it is to be fitted. The upper, or outer end of the tube is crimped inwardly in order to present a rounded upper end which will not interfere with the unwinding of the thread. A tube thus formed is placed in a suitable gluing 10 apparatus, which spreads a thin uniform layer of glue around that end of the tube remote from the rounded end, and of a width about equal to the cylindrical interior surface of the prepared cone.

10 The crimped end of the tube is now thrust into the large end of the cone 28 and through the cylindrical bore at the small end thereof, and the tube 52 is placed over the arbor 31, as shown in Fig. 6. The operator now 15 presses foot lever 49, which throws in clutch 47 and drives shaft 41 through one revolution, whereupon the clutch is thrown out and the shaft stopped. The revolution of shaft 41 of course moves the chuck 32 down from the position shown in Fig. 6 to the position 20 shown in Fig. 7 and then returns it to the former position. In the downward movement, cone 28 first seats on the conical surface 35 of the chuck and then on continued downward movement the cone is forced over the 25 tube to the position shown in Fig. 7, which is the limit of the downward movement of the chuck. In this position the cylindrical bore in the small end of the cone is over the 30 glued end of the tube.

The assembling operation is now complete, and when the chuck moves back to its upper position, the bobbin may be removed from the arbor and the operation repeated. This 35 method of assembly insures a very accurate centering of the tube and cone portions of the bobbins, as these portions are rigidly held in co-axial positions by the accurately ground surfaces 34 and 35 during the assembling 40 operation. It is to be noted that since the cone 28 is slid over the tube 52 towards the glued end, any excess of glue will be squeezed out at the interior of the bobbin and none 45 will escape to the outer surface of the bobbin.

50 By this method of manufacture a paper

bottle bobbin is produced in which the barrel and cone are perfectly co-axial and in which the exterior conical surface merges smoothly with the cylindrical surface with no shoulder at the joint.

70 The machines employed may of course be varied considerably in details of construction as the novel method can be practiced by means of apparatus, the designs and arrangement of the component elements of which 75 may be quite different from that shown and described by way of example.

Having thus described the invention, what is claimed as new and desired to be secured by Letters Patent is:

80 1. The method of joining a paper frustro-conical member to a paper tubular member to form a bottle bobbin, which consists in forming an interior cylindrical surface in the small end of the frustro-conical member 85 which meets the conical surface in a sharp feather edge and has a diameter equal to the exterior diameter of the tubular member, applying glue to the exterior surface of the tubular member at one end thereof, placing 90 the frustro-conical member over the other end of said tubular member and then while maintaining said members co-axial forcing the tubular member through the frustro-conical member until the glued end of the 95 tubular member is engaged with the cylindrical bore in the frustro-conical member.

100 2. The method of preparing a paper cone for assembly with a cylinder in the fabrication of a bottle bobbin comprising, removing the nose by a cutting operation, the cutter being introduced within the core from the large end thereof and being moved axially toward the small end to form a cylindrical axial cut entirely through the wall of the 105 cone, the exterior surface of the cone lying opposite the cut being supported against displacement during the cutting operation.

110 In testimony whereof I hereunto affix my signature.

CHARLES K. DUNLAP.
